UNITED STATES PATENT OFFICE.

HARRY B. HILLS, OF HUDSON, NEW YORK.

PORT LIGHT.

Application filed January 6, 1922, Serial No. 527,376. Renewed June 5, 1925.

To all whom it may concern:

Be it known that I, HARRY B. HILLS, a citizen of the United States, residing at Hudson, in the county of Columbia and State of New York, have invented certain new and useful Improvements in Port Lights, of which the following is a specification.

My invention relates to devices in which a cover is moved to open and close an opening, as for example, a port light for vessels. I will describe a device in the form of a port light embodying my invention and then point out the novel features thereof in 5 claims.

In the accompanying drawings, Fig. 1 is a front elevation of a port light embodying my invention. Fig. 2 is a cross-sectional view, the section being taken on the line 2-2 of Fig. 1. Fig. 3 is a detail view of the hinge connection between the light and supporting frame. Fig. 4 is a detail view of a means for lifting the cover from its seat.

Similar letters of reference designate corresponding parts in all of the figures.

A designates an annular ring which is suitably secured by bolts or rivets in an opening, which for the purposes of illustrating my invention, is formed in a ship's plating. As here shown, the ring is provided with a flange a which extends into the opening, and a second flange a^1 which is provided with a screw thread. The flange a^1 is also provided with a lip a^2 which will be referred to later. It is also provided with a seat, here shown as being in the form of a gasket G against which a cover E is evenly and firmly seated as hereinafter described. B designates a second ring which is internally screw-threaded and fits on the flange a^1 , and is provided with a flange b. The ring B is here shown as being provided with ears or lugs b^1 , b^2 , which serve as bearings for a shaft C. D designates a worm gear, as here shown, with gear teeth only on a portion of its periphery, and which is loosely mounted on the shaft C. It is held against endwise movement by the lugs b^1 , b^2 .

E designates the cover for the opening which, as here shown, comprises a frame e , in which a glass plate e^1 is secured. The cover E is provided with a pair of ears e^2 , e^3 each having an elongated opening e^4 through

which the shaft C extends. The cover E is also provided with an ear e^5 , carrying a pin e^6 which extends into an opening d provided in the worm D, the opening d being of such length that the pin e^6 can be moved inwards and outwards a short distance. It will be observed that when the worm D is rotated on the shaft C, it will cause the cover E to rotate with it through the pin e^6 , the shaft C acting as the center on which the cover E rotates.

Rotation of the worm D is caused by the engagement therewith of spiral teeth f formed on or carried by a ring F which is revolved in the casing formed by the two rings A and B. The ring F is revolved by means of the gear teeth f^1 formed on or carried by the ring F which are engaged by a spur gear f^2 , mounted on a shaft f^3 , which also carries an operating handle f^4 . The ring F is also provided with a series of wedging surfaces f^5 which co-act with a like number of wedging surfaces e^7 carried by the cover E, and which are beneath the wedging surfaces f^5 . The ring F is here shown as being confined in the ring B by means of the flange b and the lip a^2 which fits in a shouldered recess f^6 formed in the ring F. By this arrangement the ring is not only confined to its seat, but distortion of its shape is prevented, thereby insuring correct gearing engagements with the gear f^2 and worm D.

Referring to Fig. 1 which shows the cover in its closed position, by turning the handle f^4 , the ring F is revolved in its casing, and the first part of its movement causes the wedging surfaces f^5 and e^7 to be disengaged. The continued movement of the ring causes the teeth f to engage the worm D to rotate it on the shaft C, and when it rotates it carries the cover E with it to thereby uncover the opening. A reverse rotation of the handle f^4 causes the rotation of the cover E in the reverse direction to close the opening, and after the cover has reached its closed position on the gasket G, the teeth f are disengaged from the worm D. The further rotation of the ring F causes its wedging surfaces f^5 to engage the wedging surfaces e^7 , which co-act to press the frame e evenly and firmly against the gasket G, irrespective of the wear of the gasket to make a water-tight joint. This inward move-

ment of the cover E is permitted because of the elongated openings in its ears e^2 , e^3 and the lengthened opening d into which the pin e^6 extends.

5. In the event that the cover E for the opening should remain closed for a considerable period, it may be that the edge of the cover engaging the gasket G will stick fast to the gasket, and require some force to break it loose. To overcome this, I provide a lug or projection h on the frame e (see Figs. 1 and 4) which is engaged by a bevel edge h^1 , which as here shown, is formed on one of the wedges f^5 , or it may be a separate 10 projection. During the operation of the pinion f^2 to open the cover, when the wedging surfaces f^5 and e^6 are about to be or are disengaged, the edge h^1 engages the lug or projection to force or lift the frame e out 15 of engagement with the gasket G. The continued operation of the pinion f^2 raises the cover as above described.

Having thus described my invention, what I claim as new is:

25. 1. The combination with a casing for an opening; a cover for covering and uncovering the opening; a pivotal connection between the casing and cover; a ring having gear teeth for moving the cover on the pivotal connection; a shouldered recess on said ring; and a lip fitting in said recess to prevent its distortion when moving the cover on its pivotal connection.
2. The combination with a casing for an 30 opening; a cover for covering and uncovering the opening; a pivotal connection between the cover and casing; means for moving the cover on its pivotal connection comprising a ring having gear teeth; a shouldered recess on said ring; and a lip carried by the casing for fitting in said recess.
3. The combination with a casing for an 35 opening, said casing carrying a lip; a cover for covering and uncovering the opening; a pivotal connection between the cover and casing; means for moving the cover on its pivotal connection comprising a ring having gear teeth; a shouldered recess on said ring; and a second ring for holding the gear ring 40 in engagement with the lip.
4. In combination, a casing provided with an opening and with a seat, a cover for said opening, a member mounted to oscillate, means controlled by oscillation of said member for moving said cover into and out of 45 closing position against its seat, and means also controlled by movement of said member in the opening direction for separating the cover from the seat.
5. In combination, a casing provided with an opening and with a seat, a cover for said opening, a member mounted to oscillate, means controlled by oscillation of said member for moving said cover into and out of 50 closing position against its seat, a lug fixed

to the cover, and a shoulder fixed to said member and coacting with said lug to separate the cover from its seat during movement of the member in opening direction.

6. In combination, a casing provided with 70 an opening and with a seat, a cover for said opening, a member mounted to oscillate, means controlled by movement of said member in one direction for closing and locking the cover and in the other direction for unlatching and opening the cover, and means also controlled by movement of said member in the opening direction for separating the cover from its seat.

7. In combination, a casing provided with 80 an opening, a cover for said opening, a rotatable member provided with spiral teeth, a worm coacting with said teeth and provided with a transverse hole, and a pin attached to said cover and projecting into said 85 hole for moving the cover toward and away from said opening by movements of said worm.

8. In combination, a casing provided with 90 an opening, a cover for said opening, a rotatable ring, a member mounted to oscillate about an axis and provided with a transverse hole, means interposed between said ring and said member whereby rotation of the ring causes oscillation of the member, 95 and a pin attached to said cover and projecting into said hole for moving the cover toward and away from said opening by oscillation of said member.

9. In combination, a casing provided with 10 an opening, a cover pivotally attached to said casing to swing toward and away from said opening, a ring mounted to rotate in said casing, a member mounted to rotate on a shaft carried by said casing and provided with a hole transverse to said shaft, gear teeth on said ring and said member whereby rotation of the ring causes oscillation of the member, and a pin fixed to said cover and projecting into said hole whereby 11 oscillation of said member causes the cover to swing on its pivot.

10. In combination, a casing provided with an opening, a cover for said opening, a loose pivotal connection between the casing and the cover for permitting the cover to swing toward and away from the opening and also permitting straight line motion of the cover to and from the opening, a member mounted to oscillate in said casing, and provided with a hole transverse to its axis of oscillation, a pin attached to said cover and projecting into said hole whereby oscillation of said member on its axis will cause the cover to swing on its pivot without interfering with said straight line motion of the cover, and means for causing said member to oscillate.

11. In combination, a casing provided with an opening, a cover for said opening,

a loose pivotal connection between the casing and the cover for permitting the cover to swing toward and away from the opening and also permitting straight line motion of the cover to and from the opening, a member mounted to oscillate in said casing, and provided with a hole transverse to its axis of oscillation, a pin attached to said cover and projecting into said hole whereby oscillation of said member on its axis will cause the cover to swing on its pivot without interfering with said straight line motion of the cover, a ring mounted to rotate in said casing and provided with means for locking said cover in its closed position, and means associated with said ring and said member whereby rotation of the ring in reverse directions causes oscillation of the member.

20 12. In combination, a casing provided

with an opening, a cover for said opening, a loose pivotal connection between the casing and the cover for permitting the cover to swing toward and away from the opening and also permitting straight line motion of the cover to and from the opening, a member mounted to oscillate in said casing, and provided with a hole transverse to its axis of oscillation, a pin attached to said cover and projecting into said hole whereby oscillation of said member on its axis will cause the cover to swing on its pivot without interfering with said straight line motion of the cover, a ring mounted to rotate in said casing and provided with means for locking said cover in its closed position, and gear teeth on said ring and member whereby rotation of the ring in reverse directions causes oscillation of the member.

HARRY B. HILLS.
